BOAT

Kenneth W. Krutz, 498 Uppermill Heights,
Salina, Kans. 67401

Filed Mar. 15, 1971, Ser. No. 124,624

Term of patent 14 years

Int. Cl. D12—06

U.S. Cl. D71—1

FIG. 3.

FIG. 4.

FIG. 1 is an elevational view of one side of the boat embodying my new design, the opposite side being identical in appearance to that shown in FIG. 1;

FIG. 2 is a front elevational view thereof;

FIG. 3 is a top plan view thereof with a portion of the propulsion unit omitted for convenience of illustration; and

FIG. 4 is a rear elevational view thereof.

I claim:

The ornamental design for a boat, as shown and described.
